(57) **CLAIM**

The ornamental design for a desk, as shown and described.

DESCRIPTION

FIG. 1 is a top plan view of the desk showing the design; FIG. 2 is a bottom plan view thereof;

FIG. 3 is a front side elevational view thereof, the rear side elevational view being a mirror image thereof;

FIG. 4 is a left side elevational view thereof, the right side elevational view being a mirror image thereof;

FIG. 5 is a perspective view thereof, shown in a first environment of use; and,

FIG. 6 is a perspective view thereof, shown in a second environment of use.

The broken lines present in the figures are included for the purpose of illustrating portions of the article that form no part of claimed design.

1 Claim, 4 Drawing Sheets
